UNITED STATES PATENT OFFICE.

CONRAD VAUGHAN, OF CLEVELAND, OHIO, ASSIGNOR TO THE PERMOLD COMPANY, OF CLEVELAND, OHIO, A CORPORATION OF OHIO.

MOLD.

Application filed July 25, 1924. Serial No. 728,074.

This invention relates to molding apparatus and particularly to permanent metal molds.

An object of the present invention is to provide a permanent mold for casting articles of the shape requiring the use of a core and in which the core is movable downwardly out of the casting cavity.

A further object of the invention is to provide a mold particularly for casting cup-shaped articles in which the mold proper comprises complementary parts movable along a common support and in which a permanent core is movable upwardly into the casting cavity and downwardly out of same, whereby it is aided by gravity in freeing itself from the casting.

Another object of the invention is to provide such a mold in which a plurality of cup-shaped castings can be cast at the same time, the cores simultaneously removable and the mold sections simultaneously separable.

With the above and other objects in view the invention may be said to comprise the apparatus disclosed in the accompanying drawings hereinafter described and particularly set forth in the appended claims together with such variations and modifications thereof as will be apparent to one skilled in the art to which the invention appertains.

Reference should be had to the accompanying drawings forming a part of this specification in which:

Figure 1 is a top plan view of the casting apparatus.

Fig. 2 is a vertical section taken longitudinally of the frame as indicated by line 2—2 of Figure 1.

Fig. 3 is a side elevation showing the mold in open position.

Fig. 4 is a transverse vertical section taken centrally through the mold on line 4—4 of Figure 2.

Fig. 5 is a top plan view of a casting formed in one of the mold cavities.

Fig. 6 is a vertical section on line 6—6 of Fig. 5.

Referring to the accompanying drawings, the rigid frame 1 which may be bolted to the floor carries a horizontal top or bed 2 provided with side ribs 3 extending longitudinally thereof and forming between them a slideway for a pair of separable mold sec-

tions 4, 4' which are adapted to be held in engagement with each other during the casting operation and to be separated after the casting is formed. The mold sections 4, 4' are formed with recesses 5, 5' on their inner or meeting faces which extend from the bottom of the sections upwardly toward the top thereof and which when the sections 4, 4' are secured together form the casting cavities in which the castings 10 are formed. Extending upwardly from the recesses 5 are complementary recesses 6 which may widen toward the upper edges of the sections and which when the sections are secured together form relatively small sprue cavities communicating with the casting cavities by relatively small gates. As many casting cavities may be formed by recesses in the meeting faces of the two sections as may be desired. The accompanying drawing shows two such casting cavities formed between the ends of the mold sections, and, obviously, the number might be greater or less.

To center the mold sections on the supporting bed the bed 2 is provided midway between its ends with bushings 7 projecting a short distance above the bed 2 and positioned so that they are concentric with the casting cavities when the two sections 4, 4' are secured together; the mold sections 4, 4' being rabbeted at 8 along the lower edges of the recesses 5 to provide shoulders engaging the sides and tops of the bushings.

Slidably fitting in each of the bushings 7 is a core 9 adapted to be moved from a position below the top of the bushing 7 to a position within the casting cavity; the casting cavity being between the outer sections 4, 4' and the core 9, and the core and mold sections being shaped to form the inner and outer surfaces of the casting, respectively.

The casting 10 formed by the mold illustrated herein has a cylindrical skirt portion 11 and a head 12 which has a thickened portion 13 and apertures 14. To form holes in the thickened portions of the head the mold sections 4 have inwardly projecting core pins 17 which may extend into engagement with the core 9.

The outer or lower end of the skirt 11 of each casting rests on a bushing 7 so that when a core 9 is moved downwardly, as hereinafter described, the casting will be held against such downward movement.

For shifting the sections 4, 4' and for 110

holding them together two levers 18 and 19 are pivoted at one side of the bed 2 and extend across the bed on opposite sides of the bushings 7. The mold sections 4, 4' have 5 rearwardly extending flanges 20, 20' respectively, which have downwardly projecting pins 21 fixed thereto which engage in elongated slots 22 in the operating levers. The free ends of the two levers 18 and 19 project beyond the edge of the bed 2 so that they can be conveniently operated to shift the sections. The lever 18 is provided adjacent its end with teeth 23, and the lever 19 has a link 24 pivoted to the end thereof 10 which has a handle 25 at its free end and an intermediate portion 26 adapted to receive the toothed end of the lever 18, the portion 26 being provided with a detent 27 adapted to engage with the teeth of the lever 18 to lock the sections 4 together. When the mold sections 4 are in engagement with each other the two levers 18 and 19 converge toward their free ends so that by pushing the link 24 inwardly the levers exert pressure 20 upon the mold sections, the detent 27 serving to lock the sections together under pressure.

Each of the cores 9 is hollow and is secured at its lower end to a head 28 of a rigid rod 30, there being a collar 29 at the lower 30 part of the head on which the lower annular end of the core is supported. The core is secured to the head 28 by means of locking pin 28'. A removable collar 31 is secured to the collar 29 by means of screws 32 and 35 the collar 31 forms a limiting stop for limiting upward movement of the core for it extends outwardly from the rod 30 to engage the bushing 7.

The upper portion of the core 9 preferably has a separate collared pin 33 therein which provides a vent in the upper part of the core. The pin 33 may be supported by any suitable means such as a supporting pin 33' removably secured to the top of the head 28. At the sides of the core 9 are preferably located guides 34 which slide in guideways 34' formed in the bushing 7 so that the cores will not move circumferentially when being inserted into the mold or 50 withdrawn therefrom.

Racks 35 are formed on one side of each of the rods 30 and these racks mesh with an elongated pinion 36 formed on a shaft 37 which is journaled in opposite sides of the frame and extends transversely across the frame, the shaft 37 projecting from one side of the frame and having a handle 38 by means of which it may be rotated to shift the core quickly into or out of the mold, a 55 counterweight 39 being provided on an arm 39' extending from the shaft 37 which normally holds the cores in their uppermost position.

After a casting has been poured and has 60 solidified sufficiently the sections 4, 4' may be

separated by releasing the levers 18 and 19 and swinging them outwardly, the casting being retained upon the core 9. The lower edge of the casting rests upon the upper edge of the bushing 7 so that the core 9 70 may be lowered out of the casting and the casting will be left upon the supporting bed. The rack and pinion is convenient for quickly adjusting the core preparatory to pouring, but to remove the core from the casting 75 sometimes requires more force than can be conveniently applied through the rack and pinion. To loosen the core from the casting, each rod 30 has its lower end below the base member 1^a of the frame threaded and on each 80 of the threaded ends there is a nut 40.

Connected to the nuts 40 for rotative movement therewith are collars 40^a provided with sockets. The collar 40^a adjacent the operator has a pair of sockets and in one 85 of them is disposed an operating handle 41. The other socket in this collar receives an arm 41^a which actuates the arm 41^b through the connecting link 41^c, so that both of the rods 30 will loosen both of the cores from 90 the casting when the operating handle 41 is turned. As soon as the cores are loosened they can be quickly shifted to a position below the top of the bed by turning the shaft 37. 95

It will be seen from the construction illustrated, that after the pouring of a casting, the core may be first withdrawn from the casting, and the mold sections subsequently separated. This procedure is preferably in 100 the formation of castings from metal of relatively high crystallization shrinkage, since castings of such metal shrink around the core and tend to grip or "freeze" on the core unless the core is removed as rapidly as the 105 solidification of the casting will permit. The mechanism operated by the lever 41 permits the use of relatively great force to free a core from a casting engaging the core relatively tightly because of such shrinkage. 110

The feature of non-rotatability of the core is of particular advantage when the core is withdrawn from contact with the casting relatively shortly after the casting operation, since in such case, due to said non-rotatability, the core may be withdrawn without danger of injury to a partly cooled fragile casting, even though the interior of such casting and the exterior of such core, be irregular or intricate in shape, such as in the 115 construction shown.

It will thus be seen that I have provided a permanent mold of advantageous characteristics whereby castings of a given predetermined shape may be readily and accurately formed.

It will further be noted that I have provided an advantageous permanent mold comprising a plurality of separable mold sections having complementary recesses forming 120

- a substantially cup-shaped mold cavity opening downwardly and having a permanent core arranged to be positioned within said mold cavity and withdrawn therefrom.
- 5 It will moreover be noted that I have provided an improved mold in which a permanent core may be readily disposed in predetermined position with respect to recessed mold sections and in which the core may be 10 readily separated from the casting after the casting operation without danger of damaging the casting, even though the exterior of the core and the interior of the casting be of irregular or intricate shape.
- 15 It will moreover be noted that I have provided a mold of characteristics particularly advantageous for the casting of metals of relatively high crystallization shrinkage and relatively low freezing point such as, for 20 example, aluminum alloys.
- In my improved mold I have furthermore provided a core which may be moved upwardly into accurately predetermined position relative to the mold sections.
- 25 It will also be seen that I have provided an improved mold in which the lower edges of an inverted substantially cup-shaped casting may be supported during the downward withdrawal of the core from the mold 30 cavity.
- It will also be seen that I have disclosed an advantageous form of permanent core provided with vents to conduct air from the mold cavity whereby the casting metal may 35 be readily caused to conform closely to the external shape of the core.
- Furthermore it is to be understood that the particular forms of apparatus shown and described, and the particular procedure set 40 forth, are presented for purposes of explanation and illustration and that various modifications of said apparatus and procedure can be made without departing from my invention as defined in the appended claims.
- 45 What I claim is:
1. The combination with a permanent mold having a cup-shaped cavity opening downwardly, of a permanent core adapted to be positioned within the cavity and adapted to be withdrawn from the mold by downward movement, said core being provided with means to prevent circumferential displacement thereof during the operation of said mold.
  - 55 2. The combination with a permanent mold having a cup-shaped cavity opening downwardly, of a permanent core adapted to be positioned within the cavity and adapted to be withdrawn from the mold by downward movement, vents providing communication from the casting cavity to the interior of the core to permit air to escape thereinto, and means to prevent circumferential displacement of said core.
  - 60 3. The combination with a permanent mold for casting cup-shaped articles from metal having a high crystallization shrinkage and relatively low freezing point, of a frame, a pair of complemental mold sections mounted for guided lateral movement on said frame, said mold sections having complemental recesses in their inner faces forming a mold cavity opening downwardly, and a permanent core adapted to be positioned within the cavity and to be withdrawn from the mold by downward movement, said core being prevented from circumferential movement during the removal of the core from contact with the surface of the casting.
  - 65 4. The combination with a permanent mold comprising a pair of supplemental mold sections mounted for lateral movement toward and from each other upon a supporting frame, of a permanent core mounted for vertical movement in the frame, said sections having complemental recesses to form a casting cavity, said core being withdrawable from said casting cavity by downward movement, and a gate disposed in said sections above said casting cavity, said core being hollow and having vents extending into the interior thereof from the casting cavity to prevent entrapment of air in said casting cavity.
  - 70 5. The combination with a permanent mold for casting cup-shaped articles, of a pair of complemental mold sections mounted for guided lateral movement on a frame, said mold sections having complemental recesses in their inner faces forming a casting cavity opening downwardly, and a permanent core vertically supported beneath the mold sections and adapted to be inserted between them to complete the mold and a part surrounding the core adapted to support the casting as the core is being withdrawn therefrom.
  - 75 6. Molding apparatus comprising a fixed support, laterally movable permanent mold sections carried by the support, means for holding said sections together and for shifting said sections in opposite directions, a vertically movable non-rotatable permanent core carried by said support adapted to be inserted between said sections by upward movement thereof, core pins carried by said sections and adapted to engage said vertically movable core.
  - 80 7. In a molding apparatus, a fixed support, a pair of separable permanent mold sections mounted upon the support, said sections being formed to provide a sprue cavity and casting cavity, a permanent core mounted on said support and movable upwardly into the casting cavity and downwardly out of contact with a casting, a rod depending from said core, said rod having a rack portion, and a pinion engaging the rack portion for shifting the core.
  - 85 8. The invention specified in claim 7 in

which said rod also has a screw threaded portion, a nut engaging the screw threaded portion and a fixed member above said nut, whereby when said nut is turned said core 5 will be shifted.

9. In a molding apparatus, a supporting bed having a guideway thereon and a raised portion intermediate the ends of the guideways, a pair of permanent mold sections 10 mounted in said guideways on opposite sides of said raised portion, said sections having complementary recesses adapted to form a casting cavity above said raised portion and to form a gate leading from a sprue cavity 15 to said casting cavity, and a vertically disposed permanent core mounted in said raised portion and vertically movable through the bed into the mold.

10. Molding apparatus comprising a fixed 20 support, a pair of laterally movable complementary permanent mold sections mounted on said support, said sections being formed to provide a plurality of mold cavities, sprue cavities and gates for each of the mold cavities, a plurality of vertically movable permanent cores carried by said support, means for simultaneously shifting the cores, and means carried by said fixed support to support castings formed in said mold cavities 25 30 while said cores are being withdrawn from said mold cavities.

11. Molding apparatus comprising a supporting bed having a guideway thereon, a pair of laterally movable, complementary, permanent mold sections mounted on said bed, said sections being formed to provide a plurality of complementary casting cavities shaped to form cup-shaped castings opening 35 40 45 downwardly, sprue cavities and gates formed in said mold sections for each casting cavity, and a plurality of vertically movable, permanent cores carried by said bed for movement upwardly into and downwardly out of said casting cavities, means carried by said supporting bed to support castings while said cores are being moved downwardly out of said casting cavities, means 50 for shifting said mold sections on said bed, and means for simultaneously moving said cores.

12. Molding apparatus comprising a supporting bed having a guideway thereon, and a raised mold centering portion intermediate the ends thereof, a pair of permanent 55 mold sections slidably mounted in the guideway on opposite sides of the raised portion, a pair of levers pivoted at one end at one side of the guideway, projecting across the runway and connected intermediate their 60 ends to said mold sections, and means connecting the levers to secure the mold sections together.

13. Molding apparatus comprising a supporting bed having a guideway thereon and 65 a raised mold centering portion intermediate

the ends thereof, a pair of mold sections slideable in the runway on opposite sides of the raised portion and adapted to engage each other over the raised portion, a pair of levers pivoted to the support on one side of the 70 guideway and projecting across the guideway, said levers being connected intermediate their ends to said mold sections, one of said levers having teeth at the end thereof and a link pivotally carried by the other of 75 said levers, said link having a detent engageable with said teeth.

14. The combination with a permanent mold comprising a pair of complementary mold sections mounted for lateral movement toward and from each other upon a supporting frame, of permanent cores mounted for vertical movement in said frame, said sections having complementary recesses to form casting cavities therein, said cores being withdrawable from said casting cavities by downward movement, said cores being mounted on vertical rods, means for engaging said rods to shift said core sections simultaneously upwardly or downwardly, 90 means to prevent rotative movement of said core sections during the vertical movement thereof, and means for simultaneously engaging said rods to move them downwardly simultaneously a limited amount to loosen 95 the cores from the castings.

15. In a permanent mold adapted for casting substantially cup-shaped articles from metal having a relatively high crystallization shrinkage and a relatively low freezing point, in combination, a support, a plurality of separable mold sections, means for guiding said mold sections into and out of predetermined molding position on said support, said mold sections having complementary recesses in their inner faces forming a substantially cup-shaped casting cavity opening downwardly, a permanent core arranged to be moved upwardly into molding position within said casting cavity and to be withdrawn downwardly therefrom, means for preventing rotative movement of said core whereby to maintain said core in definite rotative position with respect to said support and mold sections, means for limiting the extent of upward movement of said core into said casting cavity, and means for cooperating with and supporting the lower edges of a casting during the withdrawal of the core whereby the casting may remain within the casting cavity and the core be readily separated from the casting and withdrawn outwardly of the casting cavity.

16. In a permanent mold adapted for casting substantially cup-shaped articles from metal having a relatively high crystallization shrinkage and a relatively low freezing point, in combination, a support, a plurality of separable mold sections, means for guiding said mold sections into and out of prede- 125 130

terminated molding position on said support, said mold sections having complementary recesses in their inner faces forming a substantially cup-shaped casting cavity opening downwardly and a relatively small sprue cavity above said casting cavity and a relatively small gate intermediate and communicating with said sprue and casting cavities, a permanent core arranged to be moved upwardly into molding position within said casting cavity and to be withdrawn downwardly therefrom, means for preventing rotative movement of the core whereby to maintain said core in definite rotative position with respect to said support and mold sections, means for limiting the extent of upward movement of said core into said casting cavity, said core being vented to conduct air away from the casting cavity whereby the casting metal may closely conform to the exterior shape of the core, means for cooperating with and supporting the lower edges of a casting during the withdrawal of the core whereby the casting may remain within the casting cavity and the core be readily separated from the casting and withdrawn outwardly of the casting cavity.

25. In a permanent mold adapted for casting substantially cup-shaped articles from

metal having a relatively high crystallization shrinkage and a relatively low freezing point, in combination, a support, a plurality of separable mold sections mounted on said support, means for guiding said mold sections into and out of predetermined molding position on said support, said mold sections having complementary recesses in their inner faces forming a substantially cup-shaped casting cavity opening downwardly and a relatively small sprue cavity above said casting cavity and a relatively small gate intermediate and communicating with said sprue and casting cavities, a permanent core arranged to be moved upwardly into molding position within said casting cavity and to be withdrawn downwardly therefrom, said core and support cooperating whereby to limit the upward movement of the core and to prevent rotative movement of the core so that castings of intricate interior shape may be readily formed, said core being vented to conduct air away from the casting cavity whereby the casting metal may closely conform to the exterior shape of the core.

In testimony whereof, I hereunto affix my signature.

CONRAD VAUGHAN.
